TERRAZZO

Willis A. Vogel, Toledo, Ohio

Application November 23, 1934, Serial No. 754,441

12 Claims. (CL 94—17)

This invention relates to construction materials.

This invention has utility when incorporated in terrazzo surfaces.

5 Referring to the drawing:

Fig. 1 is a section through a lower corner of a structure having a decorative terrazzo covering;

Fig. 2 is a plan view of a section of terrazzo embodying features of the invention herein;

10 Fig. 3 is a view on the line III—III, Fig. 2;

Fig. 4 is a perspective view of a section of a pre-formed decorative strip of the invention herein, showing features of interlocking;

Fig. 5 is a plan view of a pre-formed decorative 15 strip embodying a modified interlocking means;

Fig. 6 is a section on the line VI—VI, Fig. 5;

Fig. 7 is a section through a multi-strip decorative unit; and

Fig. 8 is a view similar to Fig. 4 showing a modified form of interlocking means.

20 In the installation of terrazzo, the necessary work performed is greatly facilitated by the use of pre-formed construction units of the invention herein, and at the same time the beauty of the finished work is enhanced and maintained. Decorative units produced by the invention herein become such an integral part of the entire terrazzo body that the resulting surface appears to be one continuous terrazzo unit, while still maintaining the artistic designs which may be laid out 25 therein.

The entire terrazzo body is maintained free from cracking or shrinkage, especially around the outlines of the decorative units. Furthermore, 30 means are provided for anchoring the various decorative units with the support so that there is freedom from loosening of even small inserts. In addition thereto, the coloring of the surface and the inserts can be blended more desirably.

35 Primary support 1 has sub-grade coating or foundation 2 of cementitious material spread thereon and allowed to dry sufficiently that it will support the load of workmen operating thereon to lay the terrazzo and yet be soft enough to receive the interlocking means employed between this coating and the terrazzo. Final setting or 40 hardening of this foundation 2 then serves to permanently lock the finish terrazzo coating with its decorative units thereto. Wherein the decorative

45 coating is to extend over a wall as well as upon a floor, scratch coat of plaster 3 may be provided to which the finished decorative surfacing may be attached in a like manner. The design 50 of the surface coating of terrazzo is predetermined and the decorative units may be pre-

formed to comprise a corner strip 4, a wainscot cap 5, a decorative unit 6, medallion 7, or any other decorative or construction form desired. To this end, it has been found that the body of these units should preferably be of a hardness comparable with the hardness of the finished terrazzo in which these bodies may serve as inlays, borders or other construction units. A plastic may be used, preferably rubber vulcanized to such a hardness.

5 The hardness is preferably of the standard of 90 to 95 as compared to a standard of 100 for steel when measured by a rubber hardness testing device known as a "durometer". With the pre-formed bodies of this hardness, such may be placed 10 into position by various fastening means herein-after described and the terrazzo body 8 cast upon the sub-coat 2 to the desired thickness.

15 In practice, when this terrazzo coating has set sufficiently, the grinding or polishing operation 20 takes place, and the material of the pre-formed bodies is ground and polished simultaneously with the terrazzo body 8 to form a continuous smooth surface. The material, as herein disclosed, being of a comparable hardness with the terrazzo, a 25 continuous smooth floor results without excessive wearing away of the decorative bodies and at the same time such do not chip to become pitted by this operation. Also, the resulting terrazzo is not affected by continuous cleaning operations even 30 though strong acids or alkali are employed.

The decorative bodies may be impregnated with aggregate which may be either granule, chip or dust, of terrazzo or other minerals; the impregnating particles being in some instances of the 35 same size as the surrounding terrazzo body, so that, on completion of the floor, a continuous unbroken terrazzo extent is provided. By impregnating the decorative bodies, the plastic presents a color identical with the surrounding body or 40 a contrasting color as desired, and the particles of aggregate at the surface of the decorative strips prevent excessive wear thereof.

45 In the molding or extruding of the pre-formed shapes, the aggregate with which the bodies are impregnated may extend throughout the body or be confined to the exposed surface in the finished coating.

The decorative units may have a wide range of 50 appearance. For example, the medallion 7 herein may have its main portion vulcanized rubber, impregnated with particles of rubber of a contrasting color and additionally it may have central pocket 9 which may be filled with terrazzo 55 or a

contrasting color of plastic. The pre-formed bodies may be provided with grooves 11 as herein shown in the ring body 6, which may be filled with metal 12. The lower portion of the pocket 11 is 5 provided with enlargement 13 so that the metal 12 is locked therein.

The pre-formed body may comprise polygonal cross section strips 14 or narrow strips 15. Units 10 may be pre-formed comprising a series of contrasting colors as shown in Fig. 7 herein, where a single strip of the plastic 16 may have strips 17, 18, vulcanized thereto to form a unit. The vulcanizing may be augmented by interlocking means 20, herein shown as a wire. The designs are 15 limitless and allow the terrazzo casts to directly contact the pre-formed bodies so that there is no opening of cracks along the outlining.

Various fastening means may be employed for 20 interlocking these pre-formed bodies with the sub-grade 2. There is herein shown strip 14 being provided with openings 21 therethrough, through which metallic strips 22 may be inserted at desirable distances; the clips 22 being attached to the support by means of nails 23.

25 The pre-formed members 15 may be of such a width as is shown by member 15 as to directly extend into the support therefor. Openings 24 may be provided so that the material of the support can flow therethrough for permanently locking the strip therewith. A desirable fastening means may be provided by having a metallic strip 25 partially embedded in the pre-formed bodies to extend as a fin therefrom. Where rubber is used, the body may be vulcanized to the strip.

30 Openings 26 may be provided in the strip for the plastic to flow therethrough, thus increasing the locking of the strip therewith. Additional openings 27 in the exposed fin portion allow the supporting cast to flow therethrough, and upon setting permanently, lock the fin therewith. The metallic strip 25 may be provided with bead 28 or with offsets 29 or 30 in the pre-formed bodies as additional locking means. In some instances screws 31 may be inserted in the pre-formed bodies 40 as the interlocking means. The construction units, such as corner member 4, may be provided with spaced fins 32 provided with openings 27 which may have cementitious mounting means 18 extending therethrough to lock such in position. The forms may also be provided with openings through which nails 33 may be driven into a supporting surface 34 when such is of wood or like material. The strips 14 additionally may be provided with lugs 35 or with grooves 36 with which alternative strips may have tongue and groove assembly. This provides additional interlocking means and likewise the tongues 35 or the grooves 36 allow the terrazzo cast to become directly interlocked therewith.

45 50 55 60 Triangular cross section teeth or lugs 37 may be provided as shown in Fig. 4, or such may be semi-circular cross sectional lugs 38 as shown in Fig. 8, and be either singular or multiple.

In instances wherein it is not desired to have 65 the fins 28 directly fixed with the decorative strip, clips may be provided comprising base plate 39 having lugs 40 extend upward therefrom to grip the grooves 36 of the strip 14 and fins 41 extend 70 outwardly from the plates to receive nails 42 driven into the supporting surface. Additionally, fins 43 may extend from the plate 39 into the sub-grade coating.

The fin 25 may extend centrally from the 75 pre-formed bodies or have offset 44. This fea-

ture is desirable where the plan of design is marked on the supporting surface before the terrazzo cast. The decorative units may be placed adjacent each other in contrasting colors or to obtain any desired width or may be separated with intermediate terrazzo filler or a finish plaster or cement coating 45.

There is thus provided a pre-formed decorative layout which, through the locking means, is intimately held not only directly by the terrazzo 10 cast but by mechanical means entirely cut of sight in the finished work.

The materials employed in the terrazzo insert units or dividers is hard rubber tempered to match the terrazzo hardness in which it is 15 to be used, as herein set forth, or those classes of plastics which have an amorphous or a homogeneous internal body structure, such as phenolic resins, caseins, heat-hardened nitrogenous resins and the like, capable of withstanding attack from those forces to which a terrazzo floor is normally subjected. The term "plastic" as so used is directed to that class of materials as distinguished from the materials used in the terrazzo as various cements.

25 What is claimed and it is desired to secure by Letters Patent is:

1. In combination with a terrazzo surface, a decorative insert comprising a hard rubber body, said body being tempered to a hardness to approximately match the hardness of the terrazzo.

2. In combination with a terrazzo surface, a decorative insert comprising a rubber body vulcanized to a hardness approximately equal to the hardness of the terrazzo.

3. In combination with a terrazzo surface, a decorative insert comprising a plastic body, said plastic having the properties of resisting the destructive forces encountered in normal use and tempered to approximately match the hardness 40 of the terrazzo surface.

4. In terrazzo, a cementitious sub-coat, a cementitious material face, a divider for the cementitious material face, anchored with said sub-coat, said divider comprising a preformed self-sustaining plastic body having a resistance against normal material face attacking forces approximately equal to the resistance of said material face against the same forces.

5. A decorative unit for use as an insert in a 50 terrazzo surface comprising a hard rubber body impregnated with terrazzo aggregate.

6. A decorative insert for terrazzo comprising a plastic body, said plastic having the properties of resisting the destructive forces encountered 55 in normal use and tempered to approximately match the hardness of the terrazzo in which said insert is to be used, and terrazzo aggregate impregnated in said body.

7. In a terrazzo surface, a decorative insert 60 comprising a body embodying a plurality of rubber units vulcanized together, said body as a unit tempered to approximately match the hardness of the terrazzo.

8. In a terrazzo surface, a decorative insert 65 comprising a body embodying a plurality of rubber units vulcanized together, said body as a unit tempered to approximately match the hardness of the terrazzo, and additional unit interlocking 70 means in said body.

9. A terrazzo surface comprising preformed decorative units impregnated with terrazzo aggregate, and a terrazzo body cast about said units, the resulting continuous terrazzo extent 75

having an approximate equivalent surface hardness throughout.

10. A terrazzo surface including a liner flush with said surface, said liner comprising an organic plastic pre-molded rigid body of polish and form-retaining properties approximately equal with the terrazzo for maintaining surface homogeneity in service.

11. A terrazzo surface, a pre-formed molded decorative insert therein tempered to match the

durability of said terrazzo, and means interlocking said inserts with the terrazzo.

12. The combination of a terrazzo surface, having a quality of durability, a decorative insert comprising a pre-molded unit tempered to match the durability of the terrazzo, said decorative unit including means interlocking said unit with the terrazzo.

5
